CHRISTMAS TREE DECORATION

Bernard F. Muldoon, Mountain View, N. J., assignor to Henry Hyman, Brooklyn, N. Y.

Application October 24, 1936, Serial No. 107,331

2 Claims. (Cl. 240—10)

This invention relates to a device which, when lighted up, simulates the appearance of a decorated Christmas tree.

The device comprises a base upon which an electric lamp socket is mounted in such position that the light that is screwed into the socket is inside of a conical enclosure, also mounted on the base and which has openings or perforations therethrough that are covered with thin sheets of translucent material of different colors. The cone is also provided at the top with a colored glass tip. Provision is also made to prevent light from the lamp bulb in the cone from showing around the base, and, at the same time, air passages are provided for preventing the device from becoming overheated.

The invention will be understood from the description in connection with the accompanying drawing, in which Fig. 1 is a side view of an illustrative embodiment of the invention; Fig. 2 is a section along the line 2—2 of Fig. 3 and Fig. 3 is a section along the line 3—3 of Fig. 1.

In the drawing, reference character 1 indicates a base which may be made of hollow metal for example. The base is provided with a top 2 of metal in the shape of a flat disk. A larger hollow disk 3 of metal surrounds the plate 2 and its inner edge overlaps the outer edge of the plate 2. The outside edge of the disk 3 is provided with downturned lugs 4 by means of which the cone 5 of opaque material, such as cardboard or metal for example, is attached by means of rivets 6.

An electric light socket 7 is mounted on the plate 2 above the base 1 and is attached to the plate 2 by means of screws 8. Electric wires (not shown) are connected to this socket in the usual way. An electric light bulb 9 is shown for the socket 7. A tip 11 of colored glass is inserted at the apex of the cone 5.

The socket 7 and bulb 9 can be inserted in the cone through the opening 10 in the plate 3. The outer edge of the plate 2 is provided with a slot 12 so that the edge can be slid (Fig. 3) under one of the loosened screws 2' in the plate 3, whereupon the enlarged opening 13 near the other edge of the plate 2 passes over the head of the other loosened screw 2' and the disk 2 is turned slightly to cause this screw 2' to enter the recess 15 in the side of the hole 13, whereupon the screws 2'

are tightened to keep the device in assembled position. Slits are made near the opening 10 of the disk 3 and portions 17 of this disk are bent inwardly distances slightly greater than the overlapping portion of the disks 2 and 3, to provide a plurality of air passages into the cone for keeping the same cool, and without letting the light escape at the bottom. The cone 5 is of opaque material and is provided with numerous openings 18 which are of different shapes, such as circles, stars, half moons, bells and other reminders of Christmas festivities. These holes 18 are closed on the inside of the cone 5 by having translucent closures 19 which cover the holes 18 and are glued or otherwise attached to the inside of the cone 5. These closures 19 are of different colors, such as red and green, so that when the light 9 is lighted, the decorations will be plainly visible and the tip 11 will also glow. The translucent material 19 may be made of the cellulose ester commonly known as Cellophane. The outside surface of the cone 5 may be decorated with spots 20 of silver colored material to produce an ornamental effect simulating the appearance of snow.

I claim:

1. In a device of the character described, a base having a disc-shaped top with its edge extending laterally outside of the upper end of said base, a cone having an annulus at its lower end with its inner edge supported by the outer edge of said disc-shaped top, means for detachably securing said annulus to said extending edge of said disc-shaped top, and an electric light socket supported by said base inside of said cone, the inner edge of said annulus being of smaller diameter than said disc-shaped top and of larger diameter than said socket.

2. In a device of the character described, a base, a plate extending across and beyond the upper end of said base, an electric lamp socket on said plate, a cone of opaque material provided with openings therethrough, an annulus for supporting said cone on said plate, means for detachably securing said plate and annulus together, means for providing air passages between the overlapping edges of said plate and disc, and translucent material on the inside of said cone covering said openings.

BERNARD F. MULDOON. 50
